UNITED STATES PATENT OFFICE.

JOTT GRANT, OF BOSTON, MASSACHUSETTS.

FRICITION-HINGE.

SPECIFICATION forming part of Letters Patent No. 430,847, dated June 24, 1890.

Application filed November 25, 1889. Serial No. 331,548. (No model.)

To all whom it may concern:

Be it known that I, JOTT GRANT, of Boston, in the county of Suffolk and State of Massachusetts, have invented a new and useful Improvement in Clamping-Hinges, of which the following, taken in connection with the accompanying drawings, is a specification.

The object of my invention is to so construct a hinge for blinds, doors, &c., that it may act as an ordinary hinge, or by the turning of a screw become a clamp for holding the door or blind in any desired position. This object I attain by the mechanism shown in the accompanying drawings, in which—

15 Figure 1 is an elevation showing my hinge attached to a blind. Fig. 2 is a horizontal section of the same, taken on line $x x$ of Fig. 1. Fig. 3 is a view showing one of the principal parts of my device.

20 In the drawings I have shown one of my hinges as applied to an ordinary blind.

A, Figs. 1 and 2, represents that part of the window-frame to which the blind-hinges are usually attached, B being the pintle-piece and 25 B' the pintle.

S S' represents the screws by which the pintle-piece is secured to the frame.

20 H H² H³, Figs. 1 and 2, indicates the strap of the hinge, the part H being screwed to the blind by screws K, while the part H² is bent so as to form an eye for the pintle. The extension H³ acts as a lever, by the aid of which a clamping action is made to take place about the pintle B'.

35 L L' L² is a lever-piece. One end L² rests on the end of the hinge-strap, as shown in Figs. 1 and 2, the other end L' bearing on the extension H³. (See Fig. 2.)

H', Figs. 1 and 2, is a part of the hinge-strap, bent up so as to pass through a hole L³ 40 made in the end of the lever-piece, and serves to assist in holding the lever-piece in place.

L⁴, Figs. 2 and 3, is a bolt attached to or made integral with the lever-piece L L' L², and passes through the blind, as shown in 45 Fig. 2. Upon the inside end of the bolt L⁴, I have a thumb-nut N, which, upon being screwed up, draws the lever-piece L L' L², so as to cause its end L' to bear against the extension H³ of the strap of the hinge, and thus 50 clamp the same to the pintle when it is desired to hold the blind in position.

To prevent the thumb-nut N from becoming detached from the bolt L⁴, I split the end of the said bolt, as shown at M, Figs. 2 and 3, 55 and after the parts are all connected and the thumb-nut N screwed onto the bolt L the split parts of the bolt at M are turned away from each other, so that the thumb-nut cannot be entirely removed from the bolt, al- 60 though it may be worked as much as may be required for clamping and unclamping the hinge.

I claim—

In a clamping-hinge, the combination of the 65 pintle B', strap H H², having an extension H³, with the clamping-lever L L' L², having a screw-bolt L⁴ and nut N, substantially as and for the purpose set forth.

JOTT GRANT.
